UNITED STATES PATENT OFFICE.

JACOB SCHINNELLER, OF PITTSBURG, PENNSYLVANIA.

APPARATUS FOR THE MANUFACTURE OF GAS.

SPECIFICATION forming part of Letters Patent No. 417,341, dated December 17, 1889.

Application filed December 10, 1888. Serial No. 293,106. (No model.)

To all whom it may concern:

Be it known that I, JACOB SCHINNELLER, a resident of Pittsburg, in the county of Allegheny and State of Pennsylvania, have invented a new and useful Improvement in Apparatus for the Manufacture of Gas; and I do hereby declare the following to be a full, clear, and exact description thereof.

My invention relates to the apparatus for the manufacture of gas, its object being to provide a simple form of gas-making apparatus for the manufacture of what is known as "oil-gas," or a gas generated from light hydrocarbons, steam, and air, its special object being to provide an apparatus in which the gas-making operation can be carried on in a manner practically continuous, and the heat from the fuel employed in heating the apparatus for gas-making and the gases generated can be utilized for the generation of steam and the heating of the air, while at the same time special means are provided for superheating the steam employed in generating the gases.

The special points of invention in my said apparatus will be set forth in the claims.

To enable others skilled in the art to make and use my invention, I will describe the same more fully, referring to the accompanying drawings, in which—

Figure 1 is a side view, partly in section, illustrating my invention. Fig. 2 is a top or plan view thereof. Fig. 3 is a face view, and Figs. 4, 5, and 6 are detail views of the valves and condenser apparatus.

Like letters of reference indicate like parts in each.

The apparatus is formed, generally stated, of two generating-chambers, and beside them two casings, each containing a steam-generator and an air-heating chamber, through which flues pass for the passage of the heated products and the gases generated, these several chambers and casings being connected, as hereinafter described. Each generating-chamber *a b* is contained in a casing *c*, of wrought metal, lined with fire-brick, this casing *c* resting on a suitable foundation and containing a mass of broken refractory material, such as broken fire-brick or equivalent material. At the upper end of the chamber *a* is the air-blast pipe *a'*, and at the upper

end of the chamber *b* is the air-blast pipe *b'*, these pipes each communicating with the valve *d* and forming mixing-chambers, into which the oil or other like hydrocarbon enters through the pipe *e*. These oil-pipes are carried upwardly through the mass of refractory material in the chambers *a b*, so that the oil in rising through said pipes shall be vaporized and ready to enter into union with the oxygen of the steam or air. Beside each chamber *a b* is the casing *f* or *f'*, each containing the boiler or steam-generator *g* and the air-superheater *h*, the boilers each having at the base thereof the fire-chambers *i* and the chambers *a b*, communicating with their respective casings *f f'* through the flues *i'*, leading from the bases of said generators to the fire-chambers *i*, so that the products of combustion and gases can pass from said generating-chambers through the flues *i'* to the fire-chambers, and during the heating up of the apparatus can mingle with the products of combustion arising from the fuel on the grates *i* and pass with the same upwardly, first through the flues of the steam-generators *g*, and thence through the flues of the air-superheating chambers *h*. The two casings *f f'* communicate with each other at their upper ends through the pipes *k'*, leading to the butterfly-valve *k*, which is shown in section in Fig. 4, and is so arranged that by the reversal thereof the products of combustion from one casing—such as *f*—can pass out through the purge-pipe *k* to the chimney, while the gases from the other casing—such as *f'*—can pass downwardly through the condenser and washer *l*, and thence through the eduction-pipe *l'* to the tank. The valve *k* can be of any suitable construction, the construction shown being well adapted for the purpose, and it being known as a "butterfly-valve," said valve being formed of the valve-chamber *m*, communicating through the openings *m'* with the pipes *k'* at the upper ends of the casings *f f'*, through the opening *m* with the washer *l*, and through the opening *m* with the purge-outlet *k*, and having the valve *n* secured to the shaft *n'*, and which is provided with the handle *n*, by which it can be turned to deflect the gases from one side to the other, as above described.

In order to maintain an air-blast in the ap-

paratus, I provide the fan or rotary blower p , which is operated by the engine r , said blower communicating by the forked pipe p' with the bases of the air-superheating chambers h in the casings $f f'$ and the pipes p^2 , leading from the upper ends of said air-superheating chambers h and communicating with the valve d , above referred to, which acts to deflect the blast from both superheaters to the one generating-chamber a or b , as desired. Said valve d is a flap-valve, as shown in Fig. 6, being pivoted at the base of the valve-chamber, as at d' , and the body d^2 of the valve being arranged to fit against the seats $d^3 d^4$, leading to the pipes a' or b' , respectively, and so cutting off the air partially or entirely from either of said generating-chambers.

Steam is carried from the boilers g to the engine through the pipe r' , and the exhaust-steam, which is preferably utilized in the manufacture of the gas, is carried by the pipe s to the two generating-chambers, separate branch pipes t leading therefrom, first through the fire-chambers i , and thence upwardly through the mass of refractory material in the respective generating-chambers, these pipes having openings at their upper ends communicating with the upper portion of their respective chambers, and as they pass through the heated fire-chambers and masses of highly-heated refractory material serving as superheaters for the incoming steam.

The exhaust-pipe s has a suitable three-way cock, as at s' , so as to direct the current of steam to whichever chamber is desired, and it has also a blow-off pipe s^2 , which is controlled by a suitable relief-valve s^3 , so that the exhaust-steam may be permitted to escape when not utilized, and when such steam is being employed in gas-making the pressure in such pipe can be regulated at will and at any given pressure.

In order to maintain an even flow of the exhaust-steam from the engine to the generating-chambers and prevent pulsations in the flow of such steam, and also to separate any watery particles from the steam and prevent their passage into the generating-chambers, I provide the tank u between the steam-engine and the three-way cock s' , and, if desired, the relief-valve may be arranged in said tank.

The operation of my improved gas-generating apparatus is as follows: To generate the steam necessary for operating the engine, ordinary coal fires can be lighted within the fire-chambers i of the casings $f f'$, and as soon as a sufficient body of steam is generated to operate the fan p oil is fed through the pipes e to the upper ends of both generator-chambers $a b$, and the air-blast from the fan p passes upwardly through the chambers h , and thence through the pipes p^2 to the valve d and into both said generator-chambers $a b$, the oil being vaporized and consumed within the upper parts of said chambers, and the refractory material in said chambers being

thus brought to the high heat proper for gas-making operations. The products of combustion passing from said generator-chambers flow through the flues i' into the casings $f f'$ and assist in generating the steam in the boilers g and heating the air in the chambers h . The apparatus being now in condition for the gas-making operation, the butterfly-valve k is turned so as to direct the gases from one casing—such as f —into the condenser l and permit the escape of the products from the other casing to the purge k^2 , and oil is then admitted in proper quantities at the upper end of the chamber a , the oil being vaporized as it passes upwardly through said pipe e by the heat of the refractory material in said chamber, and a limited quantity of air, sufficient for supporting the initial combustion desired in the upper end of said chamber, being admitted through the flap-valve d . During the gas-making operation the air can be entirely shut off from that generating-chamber by the closing of the flap-valve, or such portion as is found desirable can be admitted thereto, according to the heat of the chamber and the nature or the quality of the gas to be formed. Through the three-way cock s' steam is admitted through the pipe t within said generator a , and as it passes through the fire-chamber i of the casing and upwardly through the highly-heated refractory material in said chamber it is superheated and brought to the proper condition for uniting with the hydrocarbon vapor and forming a fixed gas. In this manner the superheated steam and oil-vapor (with or without air) are thus brought together and intermingled at a high heat in the upper portion of this chamber and the steam is decomposed, the oxygen thereof uniting with a portion of the hydrocarbon of the oil, and a rich heating-gas being formed, and as the gases and vapors pass downwardly through the highly-heated refractory material any steam or vapors which have not been broken up into gaseous form being so acted upon by the highly-heated refractory material and a fixed and permanent gas being so generated within the apparatus. This gas then flows through the flue i' into the fire-chamber i of the casing f (the supply of air to said fire-chamber having been cut off and the fire on the grate thereof permitted to die) and passes upwardly through the flues of the steam-generator g and the flues of the air-superheater h , and thence through the valve k into the washer and condenser pipe l , and in passing down through said pipe it is subjected to a spray of water, which acts to condense any vapors or other volatile impurities of the gas, the same being collected in the lower part of said condenser-pipe, and the gas then flows through the eduction-pipe l' to the tank. Meanwhile the air-blast has been continued from the rotary blower p through the air-superheaters h , and thence through the pipes p^2 , valve d , and pipe b' to the generator b , and by the admission of the

proper quantity of oil thereto the generator *b* has been held at the proper heat for gas-making, and therefore as soon as the highly-heated refractory material in the generator 5 *a* is so reduced in temperature that it will not act to form the gases the valve *k* is reversed, the steam admitted to the chamber *b* through the pipe *t* therein, and the proper quantity 10 of oil for gas-making is fed to said chamber through the pipe *e*, communicating therewith, and the gases made in the generator *b* follow the same course through the steam-generator *g* and air-superheater *h* of the casing *f'*, and thence to the condenser-pipe *l* and to the 15 tank. During this operation the generator *a* is again raised to the proper heat by the admission of the proper portions of oil and air thereto, as above described, and as soon as the refractory material in the chamber *b* is 20 cooled down the gas-making operation is resumed in the chamber *a*, the gas-making operation being thus practically continuous.

The apparatus is simple in construction and operation; can be operated continuously, 25 and so produce a large amount of gas; provides means for superheating the steam, and utilizes a large portion of the heat-units from the waste products and gases formed in generating the steam (reducing the cost of gas- 30 making in this particular) and in heating the air, and thereby provides for the cooling of said gases. The waste heat in blowing up the generating-chambers and the heated gases formed both impart their heat to raise the 35 steam and heat the air, and thus a continuous generation of steam and heating of the air are also obtained. Means are also provided for utilizing the waste or exhaust steam in gas-making and of separating the watery 40 particles therefrom.

What I claim as my invention, and desire to secure by Letters Patent, is—

1. A gas-making apparatus having a casing containing a generating-chamber, said chamber being filled with refractory material and 45 having an eduction-port at the base, and having an induction pipe or pipes to supply fluids to said chamber extending upwardly through said mass of refractory material and opening 50 above the same, substantially as and for the purposes set forth.

2. A gas-making apparatus having a casing

containing a generating-chamber provided with air, oil, and steam entrances at the upper end and filled with refractory material, 55 and having a flue at the base thereof communicating with a casing having therein a steam-generator and air-superheater, each provided with flues for the passage of the gases and products of combustion, substantially as and 60 for the purposes set forth.

3. In gas-making apparatus, the combination of two casings containing generating-chambers filled with refractory material and having air, oil, and steam passages at the upper ends and exit-flues at the bases thereof, and two air-superheating casings communicating with said exit-flues, through which the gas and products of combustion pass, and air-pipes leading from the superheating-chamber 70 of said casings to the upper ends of said generating-chambers, substantially as and for the purposes set forth.

4. In gas-making apparatus, the combination of two casings having therein steam-generators and air-superheating chambers, and a gas-condenser between said casings, and a reversing-valve communicating with the upper ends of said casings and said condenser, substantially as and for the purposes set forth. 80

5. The combination, with a gas-generating apparatus, of a steam engine or pump, a tank receiving the exhaust-steam therefrom, and pipes leading from said tank to and communicating with the generating apparatus, substantially as and for the purposes set forth. 85

6. In apparatus for generating gas, the combination, with two gas-generators and two casings having air-heating chambers therein, of a delivery-pipe leading from each air-heating chamber, said pipes being connected together, and having valve-controlled pipes leading to the generators, whereby the heated air from both air-heating chambers can be discharged into either generator, or both generators, substantially as and for the purposes set forth. 95

In testimony whereof I, the said JACOB SCHINNELLER, have hereunto set my hand.

JACOB SCHINNELLER.
